UNITED STATES PATENT OFFICE.

JOHN C. SMITH, OF CLEVELAND, OHIO.

PUMPING-ENGINE.

SPECIFICATION forming part of Letters Patent No. 628,419, dated July 4, 1899.

Application filed July 9, 1892; Serial No. 439,469. (No model.)

To all whom it may concern:

Be it known that I, JOHN C. SMITH, a citizen of the United States, residing at Cleveland, in the county of Cuyahoga and State of Ohio, have invented new and useful improvements in engines, wherein the power works against an approximately uniform resistance and is particularly adapted to that class of pumping-engines known as "non-rotative direct-acting," driven by steam or other motive agent equivalent thereof, of which the following is a specification.

In this specification I have selected and referred to steam as the motive power and have illustrated the mechanism involved in the invention as applied to a non-rotative direct-acting pumping-engine.

My invention relates to improvements in means for propelling the pumping-piston against an approximately uniform liquid resistance throughout its stroke by the varying pressure of the steam in the motor-cylinder due to shutting off the flow of steam into the steam-cylinder at any predetermined fractional point of the stroke and permitting the decreasing pressure of the expanding inclosed steam to finish it. To accomplish this purpose, I transmit the pressure on the steam-piston by a lever, levers, or their mechanical equivalents to the liquid or pumping piston by arranging the fulcrum between the pistons so that the steam-piston shall move the liquid-piston against its approximately uniform resistance with an unvarying force thereon and so that as the steam-pressure decreases after the point of cut-off is reached and admission of steam is shut off from the steam-cylinder the fulcrum of the lever shall automatically move so as to maintain the relative position of the fulcrum with relation to the power and load that the pressure on the steam-piston will move the liquid-piston at any point in the stroke with an equal pressure and uniform force.

In order to use the steam expansively in my improvement, it is first necessary that the total pressure of steam up to the point of cut-off shall be greater than the total resistance on the liquid-piston, this difference being greater as the degree of expansion is increased and the position of the fulcrum of the lever, levers, or mechanical equivalents remains

fixed up to that point bearing a relation to the ends of said lever or levers to which the power and load are applied that will enable the pressure on the steam-piston to move the liquid-piston against its approximately uniform resistance. As the total pressure on the steam-piston is greater than the resistance on the liquid-piston, the fulcrum of the lever or levers will be nearer to the power than to the load (as the power is greater than the load) where the fulcrum of the lever is stationary until the point of the stroke is reached at which the induction of steam to the cylinder is shut off. Hence to create and maintain a uniform relation between the force and effect for the remainder of the stroke the fulcrum of the lever must be so arranged as to be changed automatically, as hereinafter referred to, and moved with such relative velocity with the steam-piston to move the liquid-piston against its approximately uniform resistance through the remainder of the stroke even when the total pressure of the steam has fallen below the resistance on the liquid-piston. A corresponding change in relative velocities of the steam and liquid pistons also takes place with the change in the position of the fulcrum, the ratio being constant to the point of cut-off, the liquid-piston moving more rapidly than the steam-piston and the ratio changing when the fulcrum is moved until the end of the stroke is approached, when the liquid-piston moves more slowly.

As there is more friction to be overcome by the motive power employed, when the mechanism for operating the movable fulcrum is set in motion an adjustment is put on the machine, allowing the steam at its initial pressure to enter the steam-cylinder until after the movable fulcrum has been started and cutting off at that predetermined point which will leave sufficient steam-pressure to finish the stroke with the increased work of shifting the movable fulcrum.

That my invention may be fully understood by those skilled in the art I have fully and clearly illustrated a form thereof in annexed drawings, and although there are various relative arrangements of the principal parts of the engine to make the machine more compact I herein set forth an example of such as

will render the nature of my invention most readily understood.

Figure 1 is a plan view illustrating my improvement as applied to a double-acting single pump as distinguished from a duplex pump. Fig. 1' is a plan view showing the other portion of the same, the cylinders of which are supposed to be connected together, these two illustrations taken together forming an entirety of a plan view of the pumping-engine. Fig. 2 is a longitudinal vertical section of a portion of the engine through the bed-plate and steam-cylinders. Fig. 2' is also a longitudinal vertical section through the steam-cylinder. The respective portions of the two illustrations taken together would form an entirety of a longitudinal section of the engine. Fig. 3 is a longitudinal vertical section of one-half of the steam-cylinder, showing the position of the cut-off valve at the point at which steam is cut-off from the steam-cylinder, the dotted positions of the different parts in Figs. 1 and 1' corresponding to the position of parts in Fig. 3. Fig. 4 is a transverse section through the piston-rods, showing the bed-plate and its mechanism, together with my improved adjustable cut-off device. Figs. 5 and 6 are detailed views of said adjustable cut-off device, and Fig. 7 is a plan view showing a convenient arrangement of a duplex pumping-engine with my improvements associated therewith.

In the drawings and specification similar letters and numerals of reference designate similar parts.

Secured to a suitable plate or frame are the steam-cylinders A, Figs. 1, 1', 2, 2', 3, and 7, the liquid-cylinder B, Figs. 1, 1', and 7, and the lever or working beam c' for imparting motion from the steam-piston to the liquid-piston. The liquid-cylinder B is provided with the liquid piston or plunger B', which is made fast to the piston-rod V. The frame Y' is bolted to the bed-plate, as shown in Figs. 1, 1', 2, 2', 4, and 7, and assists in holding the mechanism which connects the cross-heads D and W, respectively, in place.

Connected at one end to the cross-head D by the rod a' and at the other end to the cross-head W by the rod b' is the lever or working beam c', which swings on the antifriction-roller c², forming a roller-fulcrum for the working beam c', as shown in the drawings. The end of the working beam c' next to the cross-head D is supported by a raised portion of the bed-plate Z', and the opposite end is supported by the radius-rods d' on each side, substantially as shown. One end of the upper radius-rod is pivoted at e' to the frame Y', and the corresponding end of the lower radius-rod is pivoted at f' to the bed-plate, while the pin g' passes through the opposite ends of the radius-rods d' and the working beam c' and the connecting-rod b'. Since the working beam c' must be guided in its movements by some means, these radius-rods d' cause the end of the working beam c' to move in the arc

of a circle and resist any forces which tend to swing it out of position. The working beam c' is provided with an interior central slot h', Figs. 1 and 2, which is preferably surrounded by a ridge, as indicated in the drawings, to provide bearings for wearing parts. In the upper surface of the working beam c' a little remote from the end of the slot h next to the cross-head D is secured the pin i', which acts as a trip in connection with a latch v', Figs. 1, 2, and 7, as hereinafter is more fully described.

Pivoted at j', Figs. 1, 2, and 7, to the frame Y' and the bed-plate is a bell-crank k', carrying the roller c² of the movable fulcrum. Said crank is bifurcated, as shown at m', Fig. 2, from the end which embraces the working beam c' to the dotted line n', Figs. 1 and 2, and the lever l' moves in the slot formed by said bifurcation. The end of the lever l' opposite the pivotal point j' is connected by means of the rod o' with the forward end or boss of the cross-head W. Projecting from the front edge of the lever l' and extending above its upper surface is a lip l².

To the bifurcated end of the lever k' is journaled the antifriction-roller c², Fig. 2, said roller being confined within the slot n', and by means of which the working beam and the movable fulcrum co-operate conjointly. The flanges k² and k³ on the upper surface of the movable fulcrum form a channel or guides for the slide p', said slide being shown as engaged with the lip l² of the lever l' and holds the movable fulcrum and the lever together through a portion of the stroke. The slide p' is pressed forward by the spiral spring q', which is held in place by the small pin s' between the head of the slide p' and the lug or ear r', secured to the lever k'.

The head of the small pin s' is received into an opening in the ear r', through which it plays as the slide p' is moved back and forth, the opposite end of the pin being attached to the slide p'. The bell-crank lever t', pivoted at t² to the lever k', is connected at one end to the head of the slide p' and at the other end to the link u', which extends from said bell-crank lever to the latch v'. The latch v' is pivoted at v² to the lever k', and the bell-crank lever t' is held in its normal position by the spring m', mounted on and secured to the lever k' at m². When the positions of the lever k' and the working beam c' change sufficiently to cause the arm of the latch v' to strike against the pin i', the movement of the latch, communicated to the bell-crank lever t' by means of the link u', will draw back the slide p', and thereby release the lever l', which will assume the position as shown by l'', Fig. 1'. Upon the release of the latch v' from the influence of the pin l' the springs w' and q' will return the latch-link mechanism to its former position. The end of the slide p' is rounded off and provided with the slot p² in order that the lever l' may return to the position first described by forcing back the slide p', with the lip l²,

without disturbing the bell-crank t' or its connection, which it can easily do, since the slot p^2 will allow the slide p' to move back and forth upon its pivotal connections with the bell-crank lever. The object of slot p^2 is to insure connection between the lever l' and lever k' , thereby causing the return of the working beam c' to its original position by the action of the friction-roller c^2 and lever k' , as hereinbefore set forth.

Although different designs of valve-gear may be used, I preferably use that which requires the least modification to adapt the present design used on direct-acting pump machinery to my improvements.

I do not show the method of moving the main valve F , as that which is in present use may be readily applied by those sufficiently skilled in the art. I show that to which my invention alludes, which is as follows: The steam-cylinder A is divided by the partition A' into the chambers 1 and 2, within which the pistons $C C$ reciprocate, respectively, in connection with the piston-rods $C' C'$, attached at their opposite ends to the cross-heads W and D . For reasons before stated the steam-chest nor method for moving main valve F is not shown, one position of which is shown in Figs. 2, 2', and 3. Directly over the partition A' is the port or outlet G for the escape of the exhaust-steam, in each side of which are the ports H and I , communicating between the steam-chest and the chambers 1 and 2. The supply of steam from the steam-chest into the ports H and I is governed by the main valve F . The ports H and I are respectively provided with the valves H' and I' and are secured to the valve-stems J and J' , which are rotated by the means hereinafter explained. In each of the valves H' and I' are the slot K and the spring K' , and by means of this construction the valves are capable of an up and down as well as rotary motion. To illustrate: The valve I' , Fig. 3, is closed and is held securely against the valve-seat by the pressure of the live steam from the steam-chest and the spring K' bearing against the stem J' ; but if the main valve F be moved to cut off the flow of steam from the steam-chest and at the same time opening the passage into the exhaust the steam above the valve I' will be practically removed and the expansion of the steam contained in the steam-cylinder will overcome the resistance of the spring K , raise the valve from its seat, and complete the passage from the cylinder into the exhaust-outlet G , as is shown in Fig. 2, chamber 1.

Bolted to the bed-plate are the rockerbearings $L L$, Figs. 1, 1', 4, and 7, to which are respectively attached the rock-shafts M and M' , each being provided with the arm N . Projecting from each arm N from the sides next to the cross-heads D and E are the ears N' and N^2 . Connection is made between the arms N and the valve-stems J and J' by means

of the rods $O O$ and the cranks $O' O'$. Secured to each end of the cross-heads D and E is the adjustable cut-off device P , having the pin P' , projecting from the sides next to the rocker-arms $N N$. The ears N' and N^2 of the rocker-arms N are not long enough to interfere with the cut-off device, nor are the pins P' of sufficient length to come in contact with the rocker-arms; but when the cross-head carries the cut-off device by the rocker-arms the pin P' strikes one or the other of the ears $N' N^2$, according to the direction in which the cross-head is traveling, and carries the rocker-arm over until the pin is clear of the ear, thereby rotating the valve.

The adjustable cut-off device P is best shown in Figs. 5 and 6. The pin P' is secured to the block Q , which is reciprocated in a groove in the body of the device by means of the screw Q' . The block Q is retained in place in the groove by the face-plates R and R' , which are attached to the main body of the cut-off device P . Upon the face-plate R is the scale S , Fig. 5, and the pointer T , projecting from the block Q above the center of the pin P' , in connection with the scale F , serves as a guide for adjusting the pin P' so as to strike the ear N' of the corresponding rocker-arm later, or vice versa, thereby cutting off steam from the cylinder later or earlier, as may be desired. The screw Q' is turned by means of the head U or otherwise.

The action of the engine is as follows: Figs. 1 and 2 show the position in the steam-cylinder, chamber 1, at the end of a stroke. Figs. 1' and 2' show the steam-piston in chamber 2 at the beginning of a stroke, with the accompanying mechanism in the relative position. The dotted lines in Figs. 1 and 1' represent the position of the general parts when the piston in chamber 2 has reached that point of the stroke in which steam is shut off from chamber 2 of the steam-cylinder, as before stated. The pin P' of the adjustable cut-off device P , which is attached for convenience to the cross-head D , comes in contact with the ear N' and throws the rocker-arm N , which closes the cut-off valve I , as shown in Fig. 3. The position which the various members will occupy at the end of the stroke of the piston in the chamber 2 and the beginning of the stroke in chamber 1 will be the exact reverse of that fully illustrated in Figs. 1, 1', 2, and 2'. Hence it is not deemed necessary to encumber this case with additional drawings to show the same. Since the valve I' is open, the steam at its initial pressure will flow from the steam-chest through the port I into the chamber 2 of the steam-cylinder A and drive the piston forward in the direction of the arrow until the point of cut-off is reached, as before described, when the valve I' is closed and the remainder of the stroke must be accomplished by the pressure of the expanding of the inclosed steam which is confined in chamber 2. The lever l' has now reached the end of the slot

in the movable fulcrum k' , (indicated by the dotted line, Figs. 1 and 2,) and the lever k' moves on the point j' , carrying the fulcrum of the working beam c' (represented by the roller c^2) with it, Fig. 2, from the extremity of the slot h' , which it originally occupied, to the opposite extremity, thereby assisting the steam-piston to complete its stroke. This result is well understood, as the nearer the fulcrum is carried to a given load the less power it will take to move said load. In this case the load is represented by the pressure on the piston B' of the liquid-cylinder B , and as the lever k' turns upon its pivot the fulcrum of the working beam c' approaches the load, and the pressure required to move the piston in chamber 2, together with the liquid-piston B' , lessens accordingly at the time when the actual pressure of steam in said cylinder is actually decreasing, which is a distinguishing feature and material advantage of my improvements. As the piston-rod V and the cross-head W are driven forward by the means stated above, the lever l' , bearing with its lip l^2 against the slide p' of the bell-crank k' , causes said bell-crank to turn upon its pivot, thus bringing the fulcrum of the working beam continually nearer the load represented by the piston in the chamber 1. When the extremity of the slot n' near the pin i' is reached by the roller c^2 , Fig. 1, then, by means of the pin i' in its engagement with the arm of the latch v' and the operative intervening parts heretofore described, the slide p' is withdrawn, thereby releasing the lever l' , which permits the working beam to finish its stroke. The piston in the chamber 1 is in the meantime driven toward the partition a' of the cylinder and forces the exhaust-steam through the ports H and G , the valve H' being lifted from its seat by the pressure of said steam, and when at the end of a return stroke the pin of the cut-off device P on the cross-head D comes in contact with the ear N^2 of the rocker-arm N the valve H is opening by rotation, the main valve F shifted by the ordinary means, as before noted, opening the port H for the admission of steam and opening the port I into the exhaust-port G . The piston in chamber 1 is now ready to make its stroke, performing the same work as that just performed by the piston in chamber 2, making the pump automatic and double-acting in its action.

A convenient form of duplex pumping-engine is shown in Fig. 7 to illustrate the application of the above-described mechanism to that class of engine.

To start the engine when the cut-off valves shut off steam from the chest to the cylinder, it is but necessary to open that cut-off which shuts off the steam by moving the rocker-arm N until the engine begins to move the piston to the end of its stroke, when it reverses its motion automatically.

What I claim, and desire to secure by Letters Patent, is—

1. The combination with the steam-piston and the liquid-piston, of a working beam pivotally connected to the respective pistons and a lever having one arm movably connected in the working beam to form a varying fulcrum therefor and the other arm connected to the liquid-piston, whereby the pressure on the liquid-piston is maintained substantially uniform by the varying position of the engagement of said lever with the working beam. 75

2. The combination with the steam-piston and the liquid-piston, of a working beam between the pistons, and a lever having an automatically-sliding connection to the working beam and positive connection to the liquid-piston, whereby the fulcrum of the working beam is constantly changed and a varying pressure of the steam operates to maintain a substantially uniform pressure of the liquid-piston by the varying position of the fulcrum of the working beam. 85

3. The combination with the steam-piston and the liquid-piston, of a working beam pivotally connected to the respective pistons, a lever having a movable fulcrum on which the working beam rocks, and means substantially as described to move the lever and change the location of the fulcrum as and for the purpose specified. 95

4. The combination with the steam-piston and the liquid-piston, of a working beam connected to the respective pistons and formed with a longitudinal way or slot, a suitably-fulcrumed lever having one arm movably engaging the slot in the working beam, and the other end connected to the liquid-piston substantially as described. 100

5. The combination with the steam-piston and the liquid-piston, of a working beam connected to the respective pistons and formed with a longitudinal slot, a suitably-fulcrumed lever having one arm movably engaging the slot in the working beam to form the fulcrum thereof, a jointed lever fulcrumed on the support of the lever engaging with the working beam and having the other arm connected to the liquid-piston, and a latch to lock the latter lever rigid with the former lever. 105 110

6. The combination with the steam-piston and the liquid-piston, of a working beam connected to the respective pistons and formed with a longitudinal slot, and provided with a pin i' , a lever k' suitably fulcrumed independent of its end connections, and having one end movably connected to slide in the slot of the working beam and constitute a fulcrum therefor, a jointed lever l', o' fulcrumed on the bearing of the lever k' and the end of the other arm connected to the liquid-piston, and a latch to hold the lever l', o' rigid with the lever k' and be released by engagement with the pin i' on the working beam as and for the purpose specified. 115 120 125

7. The combination with the steam-piston and the liquid-piston, of a working beam connected to the respective pistons, a moving

fulcrum for the working beam and radial arms having fixed bearing at one end and the other end connected to the end of the working beam, substantially as and for the purpose specified.

8. The combination with the steam-piston and the liquid-piston, of a working beam connected to the respective pistons, and mounted on a movable fulcrum, and radial arms having fixed bearings at their inner end, and having their outer ends pivotally connected to the end of the working beam and to the piston of the liquid-cylinder, substantially as and for the purpose specified.

15 9. The combination with the steam-piston and the liquid-piston, of a working beam connecting the respective pistons and formed with a longitudinal slot and provided with a pin i' at one end of the slot, the lever k' fulcrumed adjacent to the working beam and having its end loosely engaging in the slot of the working beam to constitute a movable fulcrum therefor, the jointed lever l' , o' fulcrumed on the bearing of the lever k' and

connected to the liquid-piston, and the latch v , u , t , p , all arranged to operate as specified.

10. The combination with the steam-piston and the liquid-piston, of a working beam pivotally connected to the respective pistons, a movable fulcrum on which the working beam rocks, and means for automatically shifting the fulcrum as the working beam is rocking.

11. The combination with the steam-piston and the liquid-piston of a pumping-engine, of a working beam having its ends pivotally connected to the respective pistons, a shifting fulcrum intermediate of the ends of the working beam on which the working beam rocks, and means for automatically shifting the fulcrum while the working beam is in operation, substantially as described.

In testimony whereof I affix my signature in presence of two witnesses.

JOHN C. SMITH.
